UNITED STATES PATENT OFFICE.

ECTOR L. CLARK, OF SIDNEY, TEXAS.

DITCHING MACHINE.

Application filed May 27, 1922. Serial No. 564,175.

To all whom it may concern:

Be it known that I, ECTOR L. CLARK, a citizen of the United States, residing at Sidney, in the county of Comanche and State 5 of Texas, have invented new and useful Improvements in Ditching Machines, of which the following is a specification.

The object of this invention is to provide a machine adapted for use in road and 10 race building and for ditching purposes.

A further object is to provide a type of drag, and certain novel controlling means therefor.

With the foregoing and other objects in 15 view, the invention consists in the novel construction and arrangement of elements described and claimed, it being understood that modifications may be made within the scope of the claims without departing from 20 the spirit of the invention.

In the drawings, Figure 1 is a perspective view of the machine; Figure 2 is a perspective view, from another angle; Figure 3 is a detail view showing a modified form 25 of connection between the blade and landside; Figure 4 is a perspective view showing the means for varying the elevation of wheel 38 with reference to the frame; Figure 5 is a detail showing means for adjusting 30 the position of the seat spring when the machine is tilted laterally; Figure 6 shows the manner of connecting one of the transverse elements with the blade.

The element 10 represents a blade which 35 may be about seven feet long, this element being slightly curved outwardly at its upper edge and being bevelled on the inner side of its lower edge.

The land-side of the machine is designated 40 14 and the elements 10 and 14 converge at their forward ends, a shoe 15 being located as illustrated. Bracket 16 supports a seat spring and seat 16', a slot 16" being provided to permit of adjustment according 45 to the position assumed by the machine in use.

Two pairs of adjustable braces are employed, the elements of one pair being designated 50 17 and 18, and those of the other pair being designated 19 and 20. A series of holes in one or both elements of pairs permit of varying the width of the device as a whole. Pivotal movement is provided at 21.

Beams 22 and 23 are bolted at 24, and a slot 25 is employed for permitting the angle

of the beams with reference to the plow or machine to be varied. The forward ends of the beams may be connected by a short bar or bolt 24', appearing at the right of Figure 60 1 and elsewhere.

A cutting coulter is shown at 27, being mounted in a bracket 28 having several apertures for adjustment.

The height of the machine is controlled 65 by lever 30, the pawl 31 operating in the usual manner by means of elements 32 and 33. A segment 34 with which the pawl cooperates is mounted at 35. A fork 36 is connected with the segment at 37, and the 70 wheel 38 is mounted between the elements of the fork. Braces are shown at 39 and 40, by means of the construction just described, the wheel 38 may be moved with reference to elements 10 and 14, for changing the elevation. The element 10 will be of steel, and the element 14, about twelve feet in length, 75 being of oak with a strip of steel 12 extending along the lower edge thereof.

A supporting rod 41 telescopes with reference to tube 42 and is retained by set screw 43, and a ball and socket joint 44 provides a universal movement.

An extension 47 is mounted with bolts 48 and 49, the bolt last named passing through 80 segmental slot 50, and permits of raising of the rear end of the extension, when desired.

The steel plate 10 may be about 18 inches high, and the landside about 12 inches high. The curved arm 26 at the forward end has a 85 series of apertures, and a bolt 26' passes through beam 22 and through any of the apertures, permitting the angular position of the shoe to be varied.

Having thus described the invention, I 90 claim:

1. In a device of the class described, a blade, a land-side member connected with said blade, the blade and land-side member converging with reference to each other, 100 and adjustable braces extending transversely between the blade and land-side member, beams adjustably connected with the blade and landside respectively, said beams extending upwardly and then forwardly over the upper edges of the blade and landside, and means for connecting the forward ends of the beams.

2. In a device of the class described, a blade, a land-side member extending at an 110 angle thereto, an element extending transversely between the blade and land-side

member, a segment mounted on said transverse member, a forked bracket mounted on the segment, a wheel mounted in the fork, and a lever and pawl, said lever being connected with the fork, for changing the relative elevation of the wheel and the blade, beams adjustably connected with the blade and landside respectively and connected with each other, and an upwardly extending arm connected with the landside and with one of the beams.

3. In a device of the class described, a blade, a landside member extending at an angle thereto, an element extending transversely between the blade and landside member, a segment mounted on said transverse member, a forked bracket mounted on the segment, a wheel mounted in the fork, and a lever and pawl, said lever being connected with the fork, for changing the relative elevation of the wheel and the blade,

and a device comprising a plurality of relatively adjustable members extending between the forked bracket and the landside member, and a universal joint for effecting connection between said device and the landside member. 25

4. In a device of the class described, a blade, a landside member extending at an angle thereto, a ground wheel and vertically 30 and laterally adjustable mounting means therefor, comprising a lever and fork connected therewith, the wheel being journaled in the fork, a two-part adjustable transverse device connecting the blade and landside member, means thereon for pivotally mounting the lever, and an adjustable transverse device connecting the fork with the landside member. 35

In testimony whereof I affix my signature. 40

ECTOR L. CLARK.
